LEWIS P. ROSS, OF STANDISH, NEW YORK, ASSIGNOR OF ONE-HALF TO NORTHERN IRON COMPANY, A CORPORATION OF NEW YORK.

METHOD OF NODULATING MATERIALS.

1,076,705.

Specification of Letters Patent.

Patented Oct. 28, 1913.

Application filed August 1, 1912. Serial No. 712,700.

To all whom it may concern:

Be it known that I, LEWIS P. ROSS, a citizen of the United States, residing at Standish, in the county of Clinton and State of New York, have invented an Improved Method of Nodulating Materials, of which the following is a specification.

My invention relates to the nodulization of materials such as fine ores, flue dust and cement, and its leading object is to effect the desired nodulization or clinkering without the stoppage of the mechanism and the loss attending the operations now in common use.

In the operations commonly practised, the materials are carried from the upper to the lower end of an inclined rotary kiln into the lower end of which a flame is projected, so that such materials are gradually heated to an adhesive or partially melted condition, when there is an objectionable adhesion thereof to the kiln lining, with the formation of rings which fill up the passage and stop the flow of the materials. This requires the mechanism to be stopped for the purpose of breaking out the rings or clearing out the adhering matter, which results in very considerable loss of time in the use of comparatively expensive apparatus, in frequent injuries to the lining, and in considerable expense for labor.

It is a desideratum, attained by my invention, to automatically free the kiln from adhering matter, with avoidance of the usual stoppage of the mechanism, labor charges for breaking out the rings and injuries to the linings. This is accomplished by preventing the usual comparatively uniform adhesion around the kiln lining, primarily by giving to the kiln, or a section thereof including the zone in which substantial adhesion takes place, an oscillatory movement such that the accumulation upon the lining shall vary in thickness and approximate a crescent in cross section, with the result that when the kiln is turned so that the thickest portion of the accumulation is brought to the highest position, it will fall by reason of its lack of support or the weakness of the lower section thereof.

The characteristic features of my invention are disclosed in the following description and the accompanying drawings in illustration thereof.

In the drawings, Figure 1 is a vertical

sectional view taken through the axis of a kiln embodying improvements of my invention; Fig. 2 is a plan view of the driving mechanism for the oscillating section; Fig. 3 is a sectional view taken on the line 3—3 of Fig. 1 in illustration of the switching mechanism; Fig. 4 is a diagrammatic view in illustration of the mechanism for reversing the motor by which the oscillating section is operated; and Fig. 5 is an enlarged sectional view taken on the line 5—5 of Fig. 1 in illustration of the accumulation approximating an unsupported arch, the section showing a modification in construction designed for cooling a longitudinal section of the kiln so as to reduce the accumulation in the region thereof and promote the peculiar formation designed for breaking down of its own weight.

The mechanism, as illustrated in the drawings, comprises the inclined rotary kiln section 1 carried by the rollers 2 on the foundation blocks 3 and the inclined oscillatory kiln section 4 carried by the rollers 5 on the foundation blocks 6. The upper end of the section 1 has the material to be nodulated fed thereto through the pipe 7 and discharges gas through the flue 8 to the stack 9. The section 4, of larger diameter than the section 1, receives the material, through the upper end thereof, from the concentric lower end of the section 1 and delivers the nodulated product at its lower end.

A hood 10, at the lower end of the section 4, carries a burner 11, by which a flame is delivered through the lower end of the section 4, and heating gases effect the desired condition in the materials traveling downwardly through the kiln so that it reaches the lower section in such condition that the desired balling or clinkering can be effected therein.

The section 1 is rotated by the usual circular rack 12 thereon and an engaging gear 13 operated by a gear train 14, and the section 4 is oscillated by a similar circular rack 15 thereon and an engaging gear 16 operated by a gear train 17. A reversible motor 18 drives the train 17, the motor being reversed by the actions of the arms or cams 19 and 19' of the section 4 upon the respective ends of a switch lever 20 fulcrumed on the bearing 21 and connected by the link 22 to the arm 23 of the switch 24.

The diagrammatic representation of Fig. 110

4 shows the leads 25 and 26 of the motor 18 connected by the three point switch 24' with conductors 27 and 28, the switch being thrown by the arms 23' oscillated by the link 5 22 and acting through the link 29.

As illustrated in Fig. 5, boxes 38, for the circulation of a cooling fluid, may be set in a longitudinal section of the part 4, for the purpose of reducing the temperature and 10 the adhesion in the vicinity thereof, water being conveniently supplied and discharged by means of the hose 31.

The material fed by the chute 7 to the upper end of the rotating section 1 is gradually 15 heated by the gases flowing in contact therewith as it is rolled and translated to the section 4. The oscillation of the section 4, the arc of which may be regulated by adjusting the arms 19 and 19', rolls the materials delivered thereto, back and forth, to effect the desired balling, rendered possible by the now adhesive condition of such material, and, while there is adhesion to the kiln lining, the deposit 32, as shown in Figs. 1 and 5, varies 20 in thickness circumferentially, forming a species of arch which finally falls by its own weight due to its lack of support.

Having described my invention, I claim:

1. The method of nodulizing materials in

turning kilns which consists in heating such 30 materials and rolling the same in reverse directions so that parts thereof adhering to the kiln lining shall be deposited of such irregular thickness circumferentially as to fall by reason of its lack of side support. 35

2. The method of nodulizing materials in turning kilns which consists in heating said materials and rolling the same back and forth over a concave surface by oscillating said kiln so that material adhering to the 40 kiln lining shall decrease in thickness circumferentially and fall by reason of its lack of side support.

3. The method of nodulizing materials 45 which consists in heating the same to an adhesive condition and rolling them over a concave surface in one direction and then rolling them over said surface in the reverse direction so as to form an arch of varying thickness. 50

In witness whereof, I have hereunto set my name this 19th day of July, 1912, in the presence of the subscribing witnesses.

LEWIS P. ROSS.
